UNITED STATES PATENT OFFICE.

HERBERT D. MORRIS, OF CHADDS FORD, PENNSYLVANIA.

BATTERY.

1,291,596.

Specification of Letters Patent. Patented Jan. 14, 1919.

Application filed July 19, 1918. Serial No. 245,748.

To all whom it may concern:

Be it known that I, HERBERT D. MORRIS, a citizen of the United States, residing at Chadds Ford, in the county of Delaware and State of Pennsylvania, have invented new and useful Improvements in Batteries, of which the following is a specification.

This invention relates to electric batteries, particularly to those of the inclosed type, and has for its object the provision of an electric battery consisting of a plurality of dry cells embedded in an insulating material inclosed within a suitable casing provided with a lining made of layers of suitable material whereby the cells will be amply protected from moisture, frost, heat or other injurious outside influences.

An important object is the provision of a battery of this character inclosed within a protective casing provided with a hinge cover whereby access may be readily had to the cells for adjusting the connections thereof, the cover inclosing the binding posts connected with the terminals of the cells whereby the current therefrom may be conducted to any desired location.

A further object is the provision of a battery of this character which will be simple and inexpensive in manufacture, efficient in use, durable in service and a general improvement of the art.

With these and other objects and advantages in view the invention consists in the novel construction and arrangement of parts to be hereinafter more fully described and claimed and illustrated in the accompanying drawing in which:—

Figure 1 is a vertical longitudinal section through my battery.

Fig. 2 is a cross sectional view therethrough;

Fig. 3 is a plan view with the cover removed.

Fig. 4 is a horizontal sectional view.

Referring more particularly to the drawing the numeral 5 designates the outside shell which may be formed of wood or metal or any other suitable material and provided with a lining 6 of asbestos disposed against

the inner surfaces. Disposed inwardly of 50 this asbestos lining 6 is a layer 7 of pitch commonly known as red pitch. As an additional prevention, I provide a layer 8 of suitable absorbing material disposed against the inner surface of the pitch layer 7. 55

Within the inclosure thus formed I dispose a plurality of dry cells and then pour around them molten red pitch which, upon solidifying, will hold the batteries in proper position against displacement within the 60 mass 13.

I may employ any desired number of cells and these cells may be connected in any desired manner, this detail forming no part of the present invention. 65

Disposed over a recess 14 in the mass 13 is a plate 15, preferably of metal, upon which are mounted and insulated therefrom, binding posts 16 which are connected with the terminals of the cells in any desired 70 manner and arrangement, the connecting wires being accommodated within the recess 14.

A lid 21 is hinged upon the casing and covers the plate 15 and the binding posts, the 75 lid being provided at its rear edge with holes 22 for the passage of wires carrying current from the binding posts.

From the foregoing description and a study of the drawing it will be apparent 80 that I have thus provided a battery so inclosed as to be damp proof, heat and frost proof and in which danger of short circuiting of the cells is reduced to a minimum.

It will of course be understood that I reserve the right to make such changes in the form, construction and arrangement of parts as will not depart from the spirit of the invention or the scope of the subjoined claim. 85

Having thus described my invention I 90 claim:—

A battery comprising a casing, a plurality of layers of absorbent material therein, a layer of red pitch disposed between said layers of absorbent material, a central mass of red pitch filling the space between the innermost layer of absorbent material and having its upper surface terminating below the 95

upper edges of said layers to define a cavity, a plurality of cells embedded in said mass of red pitch and having their terminals extending within said cavity, a metallic plate disposed upon the upper edges of said layers of absorbent material and covering said cavity and said cells, binding posts secured upon

and insulated from said plate and connected with the terminals of said cells, and a lid hinged upon said casing and inclosing said plate, and said binding posts.

In testimony whereof I affix my signature.

HERBERT D. MORRIS.
